G. F. BAUER.

ADJUSTABLE BRACKET OR STANDARD FOR HAY OR STOCK RACKS OR THE LIKE.

APPLICATION FILED MAR. 25, 1916.

1,210,260.

Patented Dec. 26, 1916.

UNITED STATES PATENT OFFICE.

GEORGE F. BAUER, OF LINWOOD, NEW YORK.

ADJUSTABLE BRACKET OR STANDARD FOR HAY OR STOCK RACKS OR THE LIKE.

1,210,260.

Specification of Letters Patent. Patented Dec. 26, 1916.

Application filed March 25, 1916. Serial No. 86,761.

To all whom it may concern:

Be it known that I, GEORGE F. BAUER, a citizen of the United States, residing at Linwood, in the county of Livingston and State of New York, have invented certain new and useful Improvements in Adjustable Brackets or Standards for Hay or Stock Racks or the like, of which the following is a specification, reference being 10 had to the accompanying drawings.

This invention relates to certain improvements in standards for hay racks or the like and it is an object of the invention to provide a device of this general character 15 having novel and improved means whereby the same may be easily and readily applied to or detached from the side of a wagon body and which consists of two pivotally connected members having coacting means 20 whereby one of said members may be automatically locked in various positions.

The invention consists in the details of construction and in the combination and arrangement of the several parts of my improved standard whereby certain important advantages are attained and the device is rendered simpler, less expensive and otherwise more convenient and advantageous for use, all as will be hereinafter more fully 30 set forth.

The novel features of the invention will hereinafter be definitely claimed.

In order that my invention may be the better understood, I will now proceed to 35 describe the same with reference to the accompanying drawings, wherein—

Figure 1 is an elevational view of a standard constructed in accordance with an embodiment of my invention, the adjacent side 40 of the body being shown in section, a second position of the movable member of the standard being indicated by dotted lines; and Fig. 2 is an enlarged sectional view taken substantially on the line 2—2 of Fig. 45 1 with the side of the wagon body omitted.

As disclosed in the accompanying drawings, 1 denotes the supporting member of my improved standard which is adapted to overlie the outer face of the side S of a 50 wagon body, and the upper end of said member 1 is provided with the downwardly disposed body side receiving hook 2. The member 1 is also provided with the longitudinally disposed outstanding flange 3 which is cut away, as at 4, for the purpose 55 of lightening the member 1 yet affording a

maximum of strength, and the upper extremity of the flange 3 extends above the member 1 to afford an ear 5 with which is pivotally engaged the lower extremity of 60 the elongated member 6 to which top boards or the like are adapted to be secured.

The outer face of the member 6 is provided with the longitudinally disposed rib 7 having produced therein the longitudinally directed slot 8 arranged on a predetermined curvature and having in communication therewith intermediate its length the branch slots 9 disposed inwardly relative to 65 the member 6, and the inner or lower end of the slot 8 is outwardly and laterally directed, as at 10.

Pivotally connected, as at 11, with the lower end of the flange 3 and at opposite 75 sides thereof are the parallel brace bars 12 having their upper or outer extremities tied or connected by the bolt 14 or the like which is also directed through the slot 8 of the rib 7, and it will be perceived that when 80 the bolt 14 is seated within the angular extension 10 of the slot 8, the member 6 will be maintained in a vertical position and that when the bolt 14 is positioned in the branches 9 of the slot 8, the member 6 will 85 be supported at various angles of inclination.

The brace afforded by the bars 12 are constantly urged outwardly through the medium of the expandable member 15 herein disclosed as a conventional coil spring interposed between the member 1 and the bars 12 at a point above their pivotal connection 11. As herein disclosed, the expandable member 90 15 coacts directly with a buffer member or yoke 16 which is operatively engaged with each of the bars 12. It is thought to be self-evident that the expandable member 15 affords a means whereby the member 6 is 95 automatically locked when in a vertical position.

From the foregoing description, it is thought to be obvious that a standard constructed in accordance with my invention is of an extremely simple and comparatively 105 inexpensive nature and is particularly well adapted for use by reason of the convenience and facility with which it may be assembled, and it will also be obvious that my invention is susceptible of some change and modification without material departure from the principles and spirit thereof and for this 110

reason I do not wish to be understood as limiting myself to the precise arrangement and formation of the several parts herein shown in carrying out my invention in practice.

I claim:

1. A wagon standard comprising two members pivoted together, one of said members being provided with a longitudinally disposed slot provided with a recess in one of its side walls, a brace pivoted to the second member and comprising two parallel bars having their outer ends connected with a cross member disposed through the slot of the first named pivoted member and adapted to be seated within the recess, a yoke member contacting with the bars of the brace, and an expansible member coacting with the yoke member and constantly urging the same outwardly.
2. A wagon standard comprising mem-

bers pivoted together, one of said members being cut away to afford a flange, the second member being provided with a slot provided with a recess in one of its walls, 25 bars pivotally engaged with the flange of the first named member at opposite sides thereof, a member connecting the outer portions of the bars and disposed through the slot of the second member and adapted to be seated within the recess, a yoke straddling the inner marginal portion of the flange and adapted for contact with the bars, and an expansible member coacting with the yoke for normally urging the same upwardly. 35

In testimony whereof I hereunto affix my signature in the presence of two witnesses.

GEORGE F. BAUER.

Witnesses:

R. E. McDOWELL,
Wm. J. McDowell.
